UNITED STATES PATENT OFFICE.

HERBERT SYMONDS, OF ST. LOUIS, MISSOURI, ASSIGNOR TO MESKER & BROTHIER, OF SAME PLACE.

DESIGN FOR A PINNACLE.

SPECIFICATION forming part of Design No. 18,935, dated February 19, 1889.

Application filed November 27, 1888. Serial No. 292,032. Term of patent 7 years.

To all whom it may concern:

Be it known that I, HERBERT SYMONDS, of St. Louis, Missouri, have invented and produced a new and original Design for a Pinnacle, of which the following is a specification, reference being had to the accompanying drawing, making part thereof, and showing the newly-designed pinnacle in elevation.

As it appears substantially the same from whatever quarter seen, a single view of the pinnacle suffices.

The design begins with an angled base, A, whose faces *a* are upright. Above the base is a circular part, B, whose face, generally considered, is inclined, but, described more particularly, consisting of the concave portion *b*, the inclined flat portion *b'*, and the convex portion *b''*.

The design is carried out more fully when the portions *b* *b''* are employed. The flat portion *b'*, however, is the element which characterizes this part of the design. The larger end of the part B is the lower one. It is smaller in diameter than the base. Above the part B is the circular part C. It is of an approximately hour-glass shape, having a concave neck, *c*, a base, *c'*, and a top, *c''*. The base and the top are of equal size and are similar in shape. The face *c''* of the parts is

beveled and the smaller end of each part is turned toward the neck *c*. The part C, as a whole, is smaller in diameter than the upper end of the part B. The part C in turn supports the part D whose general form approximates that of an oblate spheroid. The part D may also be said to be the equivalent of the part B doubled, the upper portion, *d*, of the part D being similar in shape and arrangement to that of the part B, and the lower portion, *d'*, of the part D being similar in shape to the portion *d*, but turned upward to meet the part *d*, as is shown. The part D supports a part, E, which in shape and arrangement is similar to that of the lower half of the part C.

The design terminates in the spherical part F.

I claim—

The design for a pinnacle herein shown and described, the same comprising the angled base A, the circular inclined part B, the circular part C, the spheroidal part D, the circular part E, and the sphere F, as set forth.

Witness my hand.

HERBERT SYMONDS.
